CLAIM

I claim the ornamental design for a garment, as shown and described.

DESCRIPTION

FIG. 1 is a front, left perspective view of the claimed design, according to one embodiment;

FIG. 2 is a rear, right perspective view of the claimed design of FIG. 1;

FIG. 3 is a front view of the claimed design of FIG. 1; FIG. 4 is a front view of the claimed design of FIG. 1 in another configuration;

FIG. 5 is a rear view of the claimed design of FIG. 1;

FIG. 6 is a left view of the claimed design of FIG. 1;

FIG. 7 is a right view of the claimed design of FIG. 1;

FIG. 8 is a top view of the claimed design of FIG. 1; and, FIG. 9 is a bottom view of the claimed design of FIG. 1. The ornamental design which is claimed is shown in solid lines in the figures. The broken line showing of the garment is for illustrative purposes only and forms no part of the claimed design. Broken lines formed by equal length dashes show unclaimed portions of the design.

Broken lines formed of unequal length dashes (i.e. dash-dot) show boundaries between claimed and unclaimed portions of the design.
